BALANCED INVALID WHEEL CHAIR

Herbert A. Everest and Harry C. Jennings,
Los Angeles, Calif.

Application September 11, 1940, Serial No. 356,326

7 Claims. (Cl. 155—30)

Our invention relates to a wheel chair for an invalid of a type which may be readily propelled by the invalids themselves or may be readily pushed by an attendant. In many of these types of chairs particularly where the patient propels the chair by the hand engaging either the rim of the wheel or an auxiliary rim secured to the wheel difficulty has been experienced in rolling the chair over slight obstructions such as the edges of rugs, carpets, door sills and other slightly raised or depressed portions of a floor as occur in a house. Also if the chair is used on the street or yard it has been found somewhat difficult to move the chair over slight obstructions. This applies whether or not the chair is operated by the invalid or by an attendant. Furthermore certain of the types of invalid chairs which have for instance large main supporting wheels with relatively small casters in some types readily become unbalanced so that the invalid in the chair may tilt either forward or backward unless the chair is always being handled by an attendant or considerable care is exercised by the user to prevent such tilting. A type of chair which so readily tilts or inclines to upset is very uncomfortable particularly for invalids having no use of their lower extremities.

An object and feature of our invention is the construction of a wheel chair of the type having a pair of main large supporting wheels which may have a limited tilting movement either forwardly or rearwardly but still cannot readily upset with the invalid sitting in the chair. In order that the chair may be rolled our invention comprehends using casters which may be located both forwardly and rearwardly of the tread line of the main wheels and thus are brought into contact with a smooth ground surface when the chair tilts.

Another object and feature of our construction is in providing for the tilting so that the casters either at the front or at the rear are raised from the ground in which case the chair and the weight of the invalid is supported by the tread of the main pair of wheels and either the front or the rear casters but not both casters. Such construction therefore in normal movement has either the front or the rear casters slightly raised above a floor line allowing ready propulsion of the chair over small obstructions as for instance if the front casters are in contact with the floor and meet an obstruction the chair may be tilted backwardly to raise such front casters contacting the rear casters with the floor.

An additional object and feature of our inven-

tion is constructing the chair to be substantially balanced when an invalid is sitting on the seat in an substantially upright position whereby the center of gravity is in line with the vertical plane through the axles of the main wheels. This causes most of the weight of the invalid and the chair to be supported by the tread of the main wheels with very little weight or pressure on the caster wheels hence the chair may readily be rocked or tilted by the invalid leaning either slightly forwardly or rearwardly.

Another object and feature of our invention is mounting the main and the caster wheels on an ample frame or frames which may be attached to a conventional chair and thus turn such chair into a wheel chair. This construction enables a wheel chair to be made quite inexpensively and by using a conventional type of folding chair with our frames attached thereto a readily collapsible wheel chair may be constructed. Considered in more detail our simple frames comprise a bottom bar to which the caster wheels at one side may be connected at the front and the rear and a vertical post connected substantially at the mid position, the post and the bottom bar having suitable connections to the sides of the chair whether rigid or folding and the main wheels are mounted on axles connected to the posts. This type of frame may be readily bolted to a chair.

Our invention is illustrated in connection with the accompanying drawing in which:

Fig. 1 is a side elevation showing the wheeled frame attached to the frame of a folding chair.

Fig. 2 is an elevation of one of the frames for the wheels looking from the inside, the wheels being removed.

Fig. 3 is a horizontal section through the wheel post on the line 3—3 of Fig. 2 in the direction of the arrows, the axle being omitted.

In our construction and for the sake of simplicity and to adapt the construction to chairs which may be owned by the invalid or purchased, we employ a frame designated by the assembly numeral 11. This has a bottom bar 12 (note particularly Fig. 2). In this instance it is made of a tube. A post 13 extends upwardly from the center of the bottom bar and is illustrated as secured thereto by a weld. The bottom bar is provided with perforations 14 through which bolts 45 may be passed for attaching the chair as hereunder detailed. The post also has a perforation 15 at the top through which a bolt may be fitted for attachment to the chair. Adjacent each end of the bottom bar there are further perforations 16 by which the casters may be attached using a

bolt or a screw. An axle housing 20 is built into the post 13 by perforating the post at 20' and 20'' and fixing a sleeve 21 therein. Such sleeve is internally threaded as indicated at 22 and has one end 23 projecting beyond the post 13, the sleeve being secured in place by welds, hence the axle is engaged in these threads 22 and secured by a lock nut, the wheel being on the side of the projection 23. As the sleeve 21 is firmly secured in the perforations 20' and 20'' of the tubular post 13 by welding, this sleeve forms a rigid support for an axle. The sleeve is threaded at the inner portion internally as at 22, that is, the portion facing towards the center of the chair, therefore the axle 26 of the wheel which is likewise threaded at its inner end is inserted in the sleeve and engaged in the threads 22, the axle being threaded through the sleeve a sufficient distance so that its inner threaded end is engaged by a lock nut. By this construction the hub of the wheel may be brought to have a desired working fit against the outer projecting portion 23 of the sleeve 21.

Referring to the wheel assembly as shown in Fig. 1, the pair of main wheels 25 have axles 26 secured in the sleeve 21 of the posts, these axles being in horizontal alignment. The tread 27 of the wheel is illustrated as contacting a horizontal surface such as a floor. The front caster assembly 30 is secured to one end of the frame 11, there being two of these frames, one for each side and the rear caster assembly 31 is attached to the rear of the frame. By this construction it is preferable to have a pair of front and a pair of rear casters. It will be noted in the illustration that the tread of the front casters is shown in contact with the horizontal ground surface and the tread of the rear caster is raised above the ground. There is in effect a tilting motion permitted on alignment with the axles secured to the respective posts.

Our running gear frame 11 having the wheels is shown attached to a chair indicated by the assembly numeral 35. In this illustration a type of folding chair is used. This has two side frames 36 both similar employing a bottom bar 37, an arm rest 38 at the top, a front leg 39 and a rear leg 40. Bolts 41 attach the bottom bar 37 of the chair to the bottom bar 12 of the frame 11, such bolts being passed through the perforations 14. A bolt 42 extends through an intermediate horizontal bar 43 connecting the front and rear legs 39 and 40. In this construction therefore the chair is only attached to the frame at the three definite points. This particular chair is shown as having front and rear cross braces 45 and 46 pivoted at the bottom as at 47 to the bottom bars 37 and connected at the top to sliding seat bars 48, these sliding vertically in the upper parts of the legs 39 and 40. The seat made of flexible material is attached to the seat bars. This is a conventional type of chair having a flexible back 49 connecting upward extensions of the rear legs 40.

While our invention is described as attached to a folding type of chair, the frames may be secured to rigid types, however when assembled the center of gravity of the chair plus the frame with the person sitting on the seat should pass substantially centrally through the vertical line through the axles and hence through the tread 27 of the large or main wheels. As the frame and hence the chair may be considered as suspended from the pivots of the main wheel axles, it is manifest that there may be a slight rocking

or tilting in a front to rear direction to permit either the front set or the rear set of casters to contact the floor. This type of chair may readily be propelled by the invalid sitting in the chair by grasping the rim of the wheel or by a rim attached to the spokes, however the chair may readily be handled by an attendant.

Presuming that the chair is being moved in a forward direction with the front casters in contact with the floor and the rear caster raised, then should the front caster meet an obstruction such as the edge of a rug, a door sill or the like, the invalid may tilt slightly backwardly to thus unbalance the chair bringing the front casters up and the rear casters down. There will then be sufficient clearance underneath the front casters to pass over most obstructions of the type encountered in using these chairs. Due to the large wheels being of much increased diameter over the casters they readily roll over the obstruction and when the rear casters meet the same obstruction the chair may be tilted upwardly to bring weight on the front set of casters raising the rear seat clear of the obstruction, therefore it will be seen that the chair may readily be used to pass over minor obstructions of the type usually met with by an invalid in progressing around the floor of a home or the like.

It will be noted also that our chair may be considered as a balanced invalid chair in that as above mentioned there is a substantial balance while the chair is being used but generally either the front or rear set of casters will contact the floor on the same plane as the tread of the large wheels. However no matter whether the invalid using the chair inclines forwardly or rearwardly, the respective casters will engage the floor and prevent the chair upsetting by rocking in a front to rear direction thus adding materially to the safety in the use of the chair.

When our frame is mounted on a folding chair of the type in which the sides come together when the chair is collapsed, it will be seen that our assembly of the attachable frame transforms a conventional folding chair of the above noted type to a folding wheel chair having the advantages of carrying in an automobile, on trains or for storage purposes.

In view of the fact that the major portion of the weight of the chair and the person therein is carried by the large wheels, there is very little pressure on either the front or rear casters, whichever contact the floor, and hence little likelihood of these casters catching on an obstruction. It is quite apparent that rigid wheels could be utilized instead of casters, incidentally making for a cheaper construction. Due to the tilting character of the chair, it can readily be turned even with rigidly mounted front and rear wheels.

Various changes may be made in the details of the construction without departing from the spirit or scope of the invention as defined by the appended claims.

We claim:

1. A wheel chair having a chair frame with a seat thereon, a wheel assembly frame including a bar with means securing said bar one on each side to the chair frame, a post extending upwardly from each bar, means securing each post to the chair frame, a pair of main wheels each having an axle mounted on a post, a caster secured to the forward and rearward portions of each bar, the wheel frame and the chair frame being adapted to pivot relative to the axles of

the main wheels to bring the front or the rear casters in contact with the same ground surface engaged by the main wheels.

2. In a chair construction in which a chair has two side frames each with legs, a bottom bar and an intermediate bar, a seat extending between the side frames, the combination of two wheel assembly frames each including a bottom bar and a post connected thereto and extending upwardly, means securing the bottom bar of the wheel frame to the bottom bar of a chair frame, means securing each post to a horizontal intermediate bar, a pair of main wheels journalled on each post, a caster at the forward and rear end of each horizontal bar of the wheel frame, the wheel frames being connected to the chair frames to permit tilting relative to the axles of the main wheels to bring either the front or rear casters in contact with the same level ground surface engaged by the main wheels.

3. In a wheel chair, a pair of wheel assembly frames each having a horizontal bar and a vertical post, means to secure such frames to a chair, a main wheel journalled on each post and a caster secured to the bar one adjacent its forward and one adjacent its rear end, the bar and post being adapted to tilt when secured to a chair relative to the axles of the main wheels to contact either the front or the rear casters with the same level ground engaged by the main wheels.

4. A wheel chair comprising a chair frame and a pair of wheel assembly frames, each wheel assembly frame having a bottom horizontal bar and a vertical post extending upwardly from substantially the mid position of the bar, means securing the bottom bar and the vertical post respectively to said chair frame, a main wheel journalled on each post and casters secured to the bar one adjacent its forward end and one

adjacent its rear end, the bar and post being adapted to tilt when secured to a chair relative to the axles of the main wheels to contact either the front or the rear casters with the same level ground engaged by the main wheels.

5. In a wheel chair a pair of wheel assembly frames each having a bottom horizontal rigid bar and a vertical post extending upwardly therefrom at substantially the center of each bar, means to secure each frame to a chair with the posts positioned at the sides of the chair, each post having a tubular sleeve transverse to the post, a main wheel having a stub axle secured in each sleeve, a caster secured to the forward and the rearward end portions of each bottom bar, the bar and the posts being adapted to tilt when it is secured to a chair relative to the axles of the main wheels to contact either the front or the rear casters with the same level ground engaged by the main wheels.

6. In a device as described a frame for a wheel chair including a pair of rigid bottom bars and a tubular post attached to each bar and extending upwardly from substantially the mid position of each bar, each post having diametrical perforations, the perforations in the two posts being in transverse alignment, a sleeve secured in the perforations of each post, a stub axle mounted in each sleeve and a wheel on each stub axle and means to secure a chair to both bottom bars and both posts.

7. In a device as described a frame for a wheel chair including a pair of tubular posts, means to attach each post to a chair at one side thereof, each post having diametrical perforations, the perforations in the two posts being in transverse alignment, a sleeve secured in the perforations of each post, a stub axle mounted in each sleeve and a wheel on each stub axle.
